UNITED STATES PATENT OFFICE.

HARRY RALPH RICARDO, OF LONDON, ENGLAND.

ROTARY PUMP OR COMPRESSOR.

1,412,091.

Specification of Letters Patent. Patented Apr. 11, 1922.

Application filed March 2, 1921. Serial No. 449,166.

To all whom it may concern:

Be it known that I, HARRY RALPH RICARDO, a subject of the King of England, and residing at London, in England, have invented certain new and useful Improvements in Rotary Pumps or Compressors, of which the following is a specification.

This invention relates to rotary pumps or compressors of the type comprising a series of cylinders disposed radially with respect to a centre about which they can be rotated these cylinders containing pistons at the end of each of which is a roller adapted to run on a circular track mounted so as to be rotatable but eccentric to the axis about which the cylinders rotate, the cylinders having inlet and outlet ports controlled by corresponding ports formed in a fixed spindle or trunnion about which the cylinders rotate.

10 In pumps or compressors of this type as previously known and constructed, there is liable to be a difficulty in effecting satisfactory lubrication if such a pump is used for the purpose of operating on certain gases 20 though these may be of a nature which will not attack iron and steel. The object of the present invention is to improve the construction of such pumps so as not only to overcome the difficulty of lubrication if the 30 pumps are used with gases of the type indicated, but also to enable a pump to be constructed which will have a high volumetric efficiency and low mechanical losses.

According to this invention the rotor 35 which carries the cylinders is mounted in ball or roller bearings which are disposed on or adjacent to the fixed trunnion or spindle about which the rotor turns in such a way that the bore or interior of the rotor 40 is not in contact with the exterior of the trunnion, a fluid-tight joint being formed between these parts by means of a liquid film or a labyrinth packing. A ball non-return valve is disposed in the trunnion 45 near the port through which the fluid on which the pump operates is delivered from the cylinders into the delivery passage which is formed longitudinally in the trunnion and by this arrangement clearance 50 losses are kept small. By this construction a single automatic delivery valve fitted in a stationary member and readily accessible at all times can be made to serve for any reasonable number of cylinders. The trunnion 55 is cooled in the part adjacent to this valve by means of a cooling liquid delivered into a

longitudinal passage which extends into the trunnion to a point adjacent to the valve. The heat which flows into the trunnion as a result of the compression of the fluid on 60 which the pump operates is removed to a considerable extent as this fluid passes through the port at a high velocity and high pressure so that it parts readily with its heat and heat is thus prevented from 65 flowing along the trunnion so as to cause thinning of the liquid packing film contained between the rotor and the trunnion.

The invention may be carried out in practice in various ways but the accompanying 70 drawings illustrate by way of example a construction that may be adopted. In these drawings

Figure 1 is a sectional elevation of the improved pump the section being taken in 75 the plane of the axis of the fixed trunnion and driving shaft.

Figure 2 is a transverse section on the line 2—2 in Figure 1 looking in the direction of the arrows. 80

Like letters indicate like parts throughout the drawings.

A trunnion A having a suitable length and diameter is fixed to and projects into one side of an outer casing which is conveniently 85 formed in two parts B and B' adapted to contain the pump. From the outer end of the trunnion and extending longitudinally through it for a substantial part of its length is a passage C from whose inner end 90 leads radially a passage C' which terminates in a delivery port C² through which the fluid can pass from the cylinders into the passage C. Near the inner end of the longitudinal passage C is a coned seat D 95 on which rests a ball D' constituting a non-return valve the ball being held on its seat by a coiled spring D² one end of which bears on the ball while the other end abuts against a shoulder formed near the end of a rod E. 100 The outer end E' of this rod constitutes a plug which closes the end of the passage C the rod itself extending along the passage which at this part conveniently has a greater diameter than the extreme inner end beyond 105 the seating D for the ball valve. The extreme inner end E² of the rod E constitutes a stop against which the ball D' will strike when lifted. From the outer end of the passage C a radial opening leads to a delivery 110 pipe F and in this opening is a coned seat F' for a ball valve F². This constitutes a sec-

ond non-return valve in the delivery branch or passage. The passage C is conveniently positioned out of the axial centre of the trunnion A. A second passage G runs parallel to the passage C longitudinally into the trunnion A from its outer end and extends beyond the end of the passage C to a point adjacent to the inner end of the trunnion. Concentrically disposed within the passage 5 G is a tube G' whose inner end which is open is preferably suitably supported and lies near the inner end of the passage while the outer end of the tube extends through a plug G² which closes the end of the passage G the 10 plug G² constituting a pipe union. Water is introduced into the end of the tube G and flows thence to the end of the passage G returning outwardly along this passage to a lateral outlet G³ which terminates in a pipe 15 union.

An inlet port H is formed in the periphery of the trunnion A nearer to the inner end of the latter than the delivery port C² these ports being suitably disposed on opposite 20 sides of the trunnion. The port H communicates through a short radial passage with the inner end of a longitudinal passage H' which extends into the trunnion from the inner end thereof. In the construction shown 25 this passage H' while being parallel with the axis of the trunnion A is eccentrically disposed with relation thereto and the end of the passage opens out into a ball bearing J on the end of the trunnion A. In some cases 30 the passage H' may be centrally disposed in the trunnion A but the arrangement illustrated permits the water passage G to be carried further towards the inner end of the trunnion than if the intake passage H' is 35 disposed on or near the axis of the trunnion. In this way the metal of the trunnion may be cooled substantially throughout its length.

The rotor is carried on the trunnion A by the ball bearing J and by a ball bearing J' disposed on the trunnion near the inner side 40 of the casing part B which carries the trunnion. The rotor comprises a sleeve K on which are carried a series of radially arranged cylinders L which, as shown in the 45 drawing, are conveniently three in number. These cylinders are formed on a cylindrical member L' having a flange L² near one end which extends between the cylinders and supports them. This flange L² is bolted to 50 a flange K' at one end of the sleeve K the flange K' having a lateral rib K² which is supported on the ball bearing J' while the other end of the sleeve K is carried by the ball bearing J. If desired radiating fins or 55 ribs may be provided which extend preferably in the circumferential direction around the rotor over the cylinders L and the flange L². The sleeve K fits on to the trunnion A but is not actually in contact with it, a fluid-tight joint between the parts being formed 60

by means of a liquid film or labyrinth packing.

The sleeve K constitutes the inner ends of the cylinders L and in this sleeve at the end of each cylinder there are formed two ports 70 K³ K⁴. The port K³ serves as the delivery port and is positioned so as to register with the delivery port C² in the trunnion A as the rotor turns on the trunnion. The port K⁴ constitutes the inlet port and is positioned 75 so as to register with the port H in the trunnion. By employing this construction for the cylinders the bores thereof can be machined right through so as to facilitate manufacture while the formation of the inlet and delivery ports is simplified. In each cylinder is a piston M of suitable construction which carries at its outer end a roller M' which lies in contact with a circular track N. This track is cylindrical and is 80 carried by a two-part casing member N' N² the inwardly curved or flanged end portions of which rest on ball bearings O and O' disposed between the member N' N² and the adjacent sides of the outer casing B B'. 85 These ball bearings O O' and the axis of the track N are eccentric with respect to the axis of the fixed trunnion A. The track N can thus rotate about an axis which is not coincident with the axis about which the 90 rotor K L rotates. The rollers M' which are interposed between the pistons M and the track N are maintained in contact with the track by the action of centrifugal force on the pistons as the rotor rotates on the 95 fixed trunnion A. Openings suitably shaped and disposed may be formed through the track-carrying member N' N² so as to permit of the inflow of the fluid on which the pump operates or as in the construction 100 illustrated the fluid may pass into the member or casing N' N² through the ball bearings O O'. The fluid enters the outer casing B B' through one or more suitably disposed 105 openings such as B² to which the fluid is led by piping. The rotor K L may be rotated in various ways but conveniently the inner end of the sleeve K is castellated as at K⁵ or formed with projections which extend beyond and 110 around the inner end of the trunnion A. A disc P or the like having a periphery which is toothed or otherwise formed to engage the castellations A⁵ on the end of the sleeve K is mounted on the inner end of a spindle P' 115 which is rotatably carried in the side member B' of the outer casing. The spindle P' is co-axial with the fixed trunnion A and is mounted in suitable bearings. On its outer end the spindle P' carries a pulley or is otherwise constructed as may be desired so that power can be imparted to it. A stuffing box is conveniently arranged where the spindle passes through the side of the casing B'. 120

- As the spindle P' is turned the rotor K L is caused to rotate on the fixed trunnion A and the pistons M which move outwardly by centrifugal force are moved inwardly by 5 the action of the eccentric track N with which the pistons make contact through the rollers M'. The fluid enters the casing at B² and passes into the interior of the member N' N² which carries the floating track 10 N whence the fluid can flow into the passage H' from the inner end of the fixed trunnion A. The fluid is then drawn by the pistons M into each cylinder L through the intake ports H in the trunnion and K⁴ in the end 15 of the cylinder when these ports register as the cylinders rotate on the trunnion. The fluid is compressed as each piston is moved inwardly by the action of the eccentric track N and when the cylinder delivery ports K³ 20 register in turn with the delivery port C² in the trunnion the fluid will travel past the non-return valve D' into the delivery passage C and thence past the second non-return valve F² into the delivery pipe F. 25 When the ports K³ K⁴ and C² H are not registering they are sealed respectively by the liquid film or labyrinth packing between the sleeve K and the trunnion A. The sealing liquid between these parts may be the 30 lubricant employed to lubricate the interior of the pump.
- The details of construction may be modified to suit requirements and the purpose for which the rotary pump or compressor is 35 to be used. The number of cylinders may vary as also the manner in which they are disposed on the member or members constituting the rotor. The floating track N which acts on the pistons may be constructed 40 and arranged in various ways and the formation of the pistons and the rollers M' or like members interposed between the pistons and the track N may be modified as found desirable. Various forms of coupling 45 other than that more particularly described above may be used between the inner end of the rotor K L and the adjacent end of the spindle P' through which power is applied to the rotor.
- 50 What I claim as my invention and desire to secure by Letters Patent is:—
1. In a rotary pump or compressor the combination of a fixed trunnion having inlet and delivery ports therein, inlet and delivery 55 passages extending longitudinally through the trunnion and communicating respectively with the inlet and delivery ports, a non-return valve in the delivery passage, a rotor which is rotatably mounted on the trunnion and comprises a plurality of radially disposed cylinders containing pistons, inlet and delivery ports in the heads of these cylinders adapted to register with the ports in the trunnion as the rotor rotates, a floating ring member rotatably carried in bear- 60
  - ings eccentric to the trunnion and the rotor the inner face of this ring member being operative on the pistons in the cylinders, an outer casing enclosing the ring member and the rotor and having an inlet thereto, and means for rotating the rotor on the trunnion as set forth. 70
  2. In a rotary pump or compressor the combination of a fixed trunnion having inlet and delivery ports therein, a single delivery 75 passage and an inlet passage extending longitudinally through the trunnion and communicating respectively with the delivery and inlet ports, a non-return valve in the delivery passage, a rotor which is rotatably mounted on the trunnion and comprises a plurality of radially disposed cylinders containing pistons, inlet and delivery ports in the heads of these cylinders adapted to register with the ports in the trunnion as the 80 rotor rotates, a floating ring member rotatably carried in bearings eccentric to the trunnion and the rotor the inner face of this ring member being operative on the pistons in the cylinders, an outer casing enclosing the ring member and the rotor and having an inlet thereto, and means for rotating the rotor on the trunnion as set forth. 85
  3. In a rotary pump or compressor the combination of a fixed trunnion having inlet 90 and delivery ports therein, a single delivery passage and an inlet passage extending longitudinally through the trunnion and communicating respectively with the delivery and inlet ports, a non-return valve positioned in the delivery passage adjacent to that end which communicates with the delivery port, a rotor which is rotatably mounted on the trunnion and comprises a plurality of radially disposed cylinders containing 95 pistons, inlet and delivery ports in the heads of these cylinders adapted to register with the ports in the trunnion as the rotor rotates, a floating ring member rotatably carried in bearings eccentric to the trunnion and the 100 rotor the inner face of this ring member being operative on the pistons in the cylinders, an outer casing enclosing the ring member and the rotor and having an inlet thereto, and means for rotating the rotor on the trunnion as set forth. 105
  4. In a rotary pump or compressor the combination of a fixed trunnion having inlet and delivery ports therein, a delivery passage and an inlet passage in the trunnion 110 the delivery passage extending longitudinally through the trunnion from the delivery port with which it communicates towards the fixed end of the trunnion and the inlet passage extending from the port 115 with which it communicates longitudinally through the trunnion in the opposite direction to the delivery passage, a non-return valve in the delivery passage, a rotor which is rotatably mounted on the trunnion and 120
  - 65

comprises a plurality of radially disposed cylinders containing pistons, inlet and delivery ports in the heads of these cylinders adapted to register with the ports in the 5 trunnion as the rotor rotates, a floating ring member rotatably carried in bearings eccentric to the trunnion and the rotor the inner face of this ring member being operative on the pistons in the cylinders, an outer casing 10 enclosing the ring member and the rotor and having an inlet thereto, and means for rotating the rotor on the trunnion as set forth.

5. In a rotary pump or compressor the 15 combination of a fixed trunnion having inlet and delivery ports therein, inlet and delivery passages extending longitudinally through the trunnion and communicating respectively with the inlet and delivery ports, 20 a non-return valve in the delivery passage, means for circulating water through the trunnion, a rotor which is rotatably mounted on the trunnion and comprises a plurality of radially disposed cylinders containing pistons, inlet and delivery ports in the heads of these cylinders adapted to register with the ports in the trunnion as the rotor rotates, a floating ring member rotatably carried in bearings eccentric to the trunnion and the 25 30 35 rotor the inner face of this ring member being operative on the pistons in the cylinders, an outer casing enclosing the ring member and the rotor and having an inlet thereto, and means for rotating the rotor on the trunnion as set forth.

6. In a rotary pump or compressor the combination of a fixed trunnion having inlet and delivery ports therein, inlet and delivery passages extending longitudinally 40 through the trunnion and communicating respectively with the inlet and delivery ports, a non-return valve in the delivery passage, a rotor rotatably carried by ball bearings on the trunnion the rotor comprising a plurality of radially disposed cylinders containing pistons, inlet and delivery ports in the heads of these cylinders adapted to register with the ports in the trunnion as the rotor rotates, a liquid film between the interior of the rotor and the exterior of the trunnion the film forming a seal for the ports in these parts, a floating ring member rotatably carried in bearings eccentric to the bearings and the rotor the inner face of 45 50 55 this ring member being operative on the pistons in the cylinders, an outer casing enclosing the ring member and the rotor and having an inlet thereto, and means for rotating the rotor on the trunnion as set forth.

60 7. In a rotary pump or compressor the combination of a fixed trunnion having inlet and delivery ports therein, a single delivery passage and an inlet passage extending longitudinally through the trunnion and communicating respectively with the delivery 65 and inlet ports, a non-return valve in the delivery passage, means for circulating water through the trunnion, a rotor which is rotatably mounted on the trunnion and comprises a plurality of radially disposed cylinders containing pistons, inlet and delivery ports in the heads of these cylinders adapted to register with the ports in the trunnion as the rotor rotates, a floating ring member rotatably carried in bearings eccentric to the trunnion and the rotor the inner 120 125 130 face of this ring member being operative

and the inlet ports, a non-return valve in the delivery passage, a rotor which is rotatably mounted on the trunnion and comprises a plurality of radially disposed cylinders containing pistons the cylinders being mounted 70 on a sleeve member which constitutes the heads of the cylinders, inlet and delivery ports in the sleeve member at the inner ends of the cylinders these ports being adapted to register with the ports in the trunnion as 75 the rotor rotates, a floating ring member rotatably carried in bearings eccentric to the trunnion and the rotor the inner face of this ring member being operative on the pistons in the cylinders, an outer casing enclosing 80 the ring member and the rotor and having an inlet thereto, and means for rotating the rotor on the trunnion as set forth.

8. In a rotary pump or compressor the combination of a fixed trunnion having inlet and delivery ports therein, a single delivery passage and an inlet passage in the trunnion the delivery passage extending longitudinally through the trunnion from the delivery port with which it communicates towards the fixed end of the trunnion and the inlet passage extending from the port with which it communicates longitudinally through the trunnion in the opposite direction to the delivery passage, a non-return valve positioned in the delivery passage adjacent to that end which communicates with the delivery port, a rotor which is rotatably mounted on the trunnion and comprises a plurality of radially disposed 90 95 100 cylinders containing pistons, inlet and delivery ports in the heads of these cylinders adapted to register with the ports in the trunnion as the rotor rotates, a floating ring member rotatably carried in bearings eccentric to the trunnion and the rotor the inner face of this ring member being operative on the pistons in the cylinders, an outer casing enclosing the ring member and the rotor and having an inlet thereto, and means for 105 110 115 120 125 130 rotating the rotor on the trunnion as set forth.

9. In a rotary pump or compressor the combination of a fixed trunnion having inlet and delivery ports therein, a single delivery passage and an inlet passage extending longitudinally through the trunnion and communicating respectively with the delivery and inlet ports, a non-return valve in the delivery passage, means for circulating water through the trunnion, a rotor which is rotatably mounted on the trunnion and comprises a plurality of radially disposed cylinders containing pistons, inlet and delivery ports in the heads of these cylinders adapted to register with the ports in the trunnion as the rotor rotates, a floating ring member rotatably carried in bearings eccentric to the trunnion and the rotor the inner face of this ring member being operative

on the pistons in the cylinders, an outer casing enclosing the ring member and the rotor and having an inlet thereto, and means for rotating the rotor on the trunnion as set forth.

10. In a rotary pump or compressor the combination of a fixed trunnion having inlet and delivery ports therein, a single delivery passage and an inlet passage extending longitudinally through the trunnion and communicating respectively with the delivery and inlet ports, a non-return valve positioned in the delivery passage adjacent to that end which communicates with the delivery port, means for circulating water through the trunnion, a rotor which is rotatably mounted on the trunnion and comprises a plurality of radially disposed cylinders containing pistons, inlet and delivery ports in the heads of these cylinders adapted to register with the ports in the trunnion as the rotor rotates, a floating ring member rotatably carried in bearings eccentric to the trunnion and the rotor the inner face of this ring member being operative on the pistons in the cylinders, an outer casing enclosing the ring member and the rotor and having an inlet thereto, and means for rotating the rotor on the trunnion as set forth.

15. In a rotary pump or compressor the combination of a fixed trunnion having inlet and delivery ports therein, a delivery passage and an inlet passage in the trunnion the delivery passage extending longitudinally through the trunnion from the delivery port with which it communicates towards the fixed end of the trunnion and the inlet passage extending from the port with which it communicates longitudinally

20. through the trunnion in the opposite direction to the delivery passage, a non-return valve in the delivery passage, means for circulating water through the trunnion, a rotor which is rotatably mounted on the trunnion and comprises a plurality of radially disposed cylinders containing pistons, inlet and delivery ports in the heads of these cylinders adapted to register with the ports in the trunnion as the rotor rotates, a floating

25. ring member rotatably carried in bearings eccentric to the trunnion and the rotor the inner face of this ring member being operative on the pistons in the cylinders, an outer casing enclosing the ring member and the rotor and having an inlet thereto, and means for rotating the rotor on the trunnion as set forth.

30. 11. In a rotary pump or compressor the combination of a fixed trunnion having inlet and delivery ports therein, a delivery passage and an inlet passage in the trunnion the delivery passage extending longitudinally

35. through the trunnion from the delivery port with which it communicates towards the fixed end of the trunnion and the inlet passage extending from the port with which it communicates longitudinally

40. through the trunnion in the opposite direction to the delivery passage, a non-return valve in the delivery passage, means for circulating water through the trunnion, a rotor which is rotatably mounted on the trunnion and comprises a plurality of radially disposed cylinders containing pistons, inlet and delivery ports in the heads of these cylinders adapted to register with the ports in

45. the trunnion as the rotor rotates, a floating

50. ring member rotatably carried in bearings eccentric to the trunnion and the rotor the inner face of this ring member being operative on the pistons in the cylinders, an outer casing enclosing the ring member and the

55. rotor and having an inlet thereto, and means for rotating the rotor on the trunnion as set forth.

12. In a rotary pump or compressor the combination of a fixed trunnion having inlet and delivery ports therein, a single delivery passage and an inlet passage extending longitudinally through the trunnion and communicating respectively with the delivery and inlet ports, a non-return valve positioned in the delivery passage adjacent to that end

which communicates with the delivery port, a rotor rotatably carried by ball bearings on the trunnion the rotor comprising a plurality of radially disposed cylinders containing pistons, inlet and delivery ports in the heads of these cylinders adapted to register with the ports in the trunnion as the rotor rotates, a liquid film between the interior of the rotor and the exterior of the trunnion the film forming a seal for the ports in these parts, a floating ring member rotatably carried in bearings eccentric to the bearings and the rotor the inner face of this ring member being operative on the pistons in the cylinders, an outer casing enclosing the ring member and the rotor and having an inlet thereto, and means for rotating the rotor on the trunnion as set forth. 70 75 80

13. In a rotary pump or compressor the combination of a fixed trunnion having 85 inlet and delivery ports therein, a single delivery passage and an inlet passage extending longitudinally through the trunnion and communicating respectively with the delivery and inlet ports, a non-return valve positioned in the delivery passage adjacent to that end which communicates with the delivery port, means for circulating water through the trunnion, a rotor rotatably carried by ball bearings on the trunnion the 95 rotor comprising a plurality of radially disposed cylinders containing pistons, inlet and delivery ports in the heads of these cylinders adapted to register with the ports in the trunnion as the rotor rotates, a liquid film 100 between the interior of the rotor and the exterior of the trunnion the film forming a seal for the ports in these parts, a floating ring member rotatably carried in bearings eccentric to the bearings and the rotor the 105 inner face of this ring member being operative on the pistons in the cylinders, an outer casing enclosing the ring member and the rotor and having an inlet thereto, and means for rotating the rotor on the trunnion as set 110 forth.

14. In a rotary pump or compressor the combination of a fixed trunnion having inlet and delivery ports therein, a single delivery passage and an inlet passage extending longitudinally through the trunnion and communicating respectively with the delivery and inlet ports, a non-return valve positioned in the delivery passage adjacent to that end which communicates with the delivery port, a rotor which is rotatably mounted on the trunnion and comprises a plurality of radially disposed cylinders containing pistons the cylinders being mounted on a sleeve member which constitutes the heads of the cylinders, inlet and delivery ports in the sleeve member at the inner ends of the cylinders these ports being adapted to register with the ports in the trunnion as the rotor rotates, a floating ring member 115 120 125 130

6
rotatably carried in bearings eccentric to the trunnion and the rotor the inner face of this ring member being operative on the pistons in the cylinders, an outer casing enclosing the ring member and the rotor and having an inlet thereto, and means for rotating the rotor on the trunnion as set forth.

15. In a rotary pump or compressor the combination of a fixed trunnion having inlet and delivery ports therein, inlet and delivery passages extending longitudinally through the trunnion and communicating respectively with the inlet and delivery ports, a non-return valve in the delivery passage, means for circulating water through the trunnion, a rotor which is rotatably mounted on the trunnion and comprises a plurality of radially disposed cylinders containing pistons the cylinders being mounted 20 on a sleeve member which constitutes the heads of the cylinders, inlet and delivery ports in the sleeve member at the inner ends of the cylinders these ports being adapted to register with the ports in the trunnion 25 as the rotor rotates, a floating ring member rotatably carried in bearings eccentric to the trunnion and the rotor the inner face of this ring member being operative on the pistons in the cylinders, an outer casing enclosing the ring member and the rotor and having an inlet thereto, and means for rotating the rotor on the trunnion as set forth.

16. In a rotary pump or compressor the combination of a fixed trunnion having inlet and delivery ports therein, inlet and delivery passages extending longitudinally through the trunnion and communicating respectively with the inlet and delivery ports, a non-return valve in the delivery passage, a rotor rotatably carried by ball bearings on the trunnion the rotor comprising a plurality of radially disposed cylinders containing pistons the cylinders being mounted on a sleeve member which constitutes the heads of the cylinders, inlet and delivery ports in the sleeve member at the inner ends of the cylinders these ports being adapted to register with the ports in the trunnion as the rotor rotates, a liquid film

between the interior of the rotor and the exterior of the trunnion the film forming a seal for the ports in these parts, a floating ring member rotatably carried in bearings eccentric to the trunnion and the rotor the inner face of this ring member being operative on the pistons in the cylinders, an outer casing enclosing the ring member and the rotor and having an inlet thereto, and means for rotating the rotor on the trunnion as set forth.

17. In a rotary pump or compressor the combination of a fixed trunnion having inlet and delivery ports therein, a delivery passage and an inlet passage in the trunnion the delivery passage extending longitudinally through the trunnion from the delivery port with which it communicates towards the fixed end of the trunnion and the inlet passage extending from the port with which it communicates longitudinally through the trunnion in the opposite direction to the delivery passage, a non-return valve in the delivery passage, means for circulating water through the trunnion, a rotor rotatably carried by ball bearings on the trunnion the rotor comprising a plurality of radially disposed cylinders containing pistons the cylinders being mounted on a sleeve member which constitutes the heads of the cylinders, inlet and delivery ports in the sleeve member at the inner ends of the cylinders these ports being adapted to register with the ports in the trunnion as the rotor rotates, a liquid film between the interior of the rotor and the exterior of the trunnion the film forming a seal for the ports in these parts, a floating ring member rotatably carried in bearings eccentric to the trunnion and the rotor the inner face of this ring member being operative on the pistons in the cylinders, an outer casing enclosing the ring member and the rotor and having an inlet thereto, and means for rotating the rotor on the trunnion as set forth.

In testimony whereof I have signed my name to this specification.

HARRY RALPH RICARDO.
